UNITED STATES PATENT OFFICE

2,089,023

FABRICATED METAL STUD

Harry W. Hahn, Glendale, Calif.

Application April 5, 1935, Serial No. 14,847

4 Claims. (Cl. 189—37)

This invention comprehends the provision of a fabricated metal stud, or structural member, of maximum rigidity and strength and of minimum weight, so designed and formed as to resist lateral stresses, as when used in a wall structure, such as are caused by winds and earthquakes and yet sufficiently resistant to the longitudinal stresses in a wall structure to prevent distortion and deformation of the wall, and withal, to provide a structure of far less weight and far greater strength and durability when used as wall studs than other types of integral metal studs or wooden members.

An object is to provide a fabricated stud composed of a pair of deeply channeled parallel side rails and one or more struts alternately bent in opposite directions and disposed in diagonal planes and firmly secured to the side rails in a simple and effective manner which may be readily and economically accomplished by machinery specially designed for the purpose, thereby permitting the complete formation and fabrication of studs at a minimum cost and without the necessity for riveting, bolting or welding of the members together.

25 A further object is to provide side rails and struts which are correspondingly beaded or ribbed so as to correspond in cross section to the end that the members will be firmly and snugly nested together at their meeting points, and otherwise so formed at such points for interlocking portions of the attached members against disengagement or relative movement in any direction.

Another object is to provide in connection with the studs a form of foot piece or header specially adapted to support the lower ends of the studs and similarly adapted to rest upon and provide a header for a series of studs when used in a wall, said member being arranged for attachment to a sill or foundation by suitable anchors when used as a foot piece or for attachment to rafters or joists as when used as a header. Other and more detailed objects of invention will appear as the description progresses.

45 I have shown a preferred form of member in the accompanying drawing, in which:

Fig. 1 is an elevation of a stud embodying my improvements in position for use, as in a wall structure, secured at its bottom to a preferred form of foot piece and at its top bearing a header similar to the footpiece;

Fig. 2 is a fragmentary section of a wall structure, on line 2—2 of Fig. 1 and showing a pair of studs suitably spaced apart and secured to a common foot piece;

Fig. 3 is a fragmentary section, in elevation, on line 3—3 of Fig. 1;

Fig. 4 is an enlarged sectional plan on line 4—4 of Fig. 1;

Fig. 5 is a fragmentary longitudinal section on line 5—5 of Fig. 3;

Fig. 6 is a fragmentary view of the strut for connecting the side rails and showing means formed thereon and adapted to cooperate with means on the rails for attaching the members together;

Fig. 7 is a cross sectional view of the strut on line 7—7 of Fig. 6;

Fig. 8 is a cross section of the side rails on line 8—8 of Fig. 3;

Fig. 9 is a view of a section of structural member of slightly modified form; and

Fig. 10 is a section thereof on line 10—10.

Each stud, or structural member includes a pair of similar side rails R and R' uniformly spaced apart throughout their length and a strut S bent so as to alternately engage the side rails, as shown in Fig. 1, or as shown in Fig. 9, a pair of struts S and S' may be similarly formed and secured to the respective side rails R and R' and to each other at spaced points.

Rails R and R' are preferably of the cross section shown in Fig. 8 with spaced sides 2, 2, right angular shoulders 3, 3, and a relatively central bead 4 of substantial depth, thereby providing a cross section of substantial strength and capable of withstanding extraordinary stresses occasioned by wind or otherwise laterally of a wall and in the direction of the sides 2.

The strut S is a cross section shown in Fig. 7 with a central bead 5 corresponding to and adapted to seat in the bead 4 of the rails R and R' and has lateral flat portions 6, 6, in a common plane and on opposite sides of the bead 5 adapted to rest firmly upon the shoulders 3, 3 of the rails, the width of member S substantially corresponding to the distance between the two sides 2, 2, of rails R and R'.

Rails R and R' have uniformly spaced rectangular perforations 7, 7, etc., from which the metal is cut and bent inwardly of the rails to form lugs 8, 8, etc., at opposite points in the sides 2, 2, so as to overlie and interlock with notched portions 9, 9, at opposite points on the edges of the strut S. It will be understood that the strut S is incapable of transverse movement relative to the rails R and R' due to the nesting of the beaded strut in the beaded rails and the interlocking of the lugs 7 with the notches 9 of the strut prevents any longitudinal movement of the strut relative

to the rails. The legs 8 are cut and bent inwardly from the flanges 2 of rails R and R' at points close to the webs 3 so as not to weaken the rails and permit buckling at folding of the flanges 5 under strains.

The members R, R' and S are adapted to be fabricated and secured together in a continuous operation and in desired lengths by means of suitable machines which clinch the lugs 8 over 10 the notches 9 while the rails and strut are held in the machine, thus contributing to the economy in production and facility of manufacture.

A single strut S is employed for each stud or structural member and is alternately bent in 15 opposite directions, as shown in Fig. 1 so as to provide alternating sections 10 and 11 at angles of approximately ninety degrees, and intermediate portions 12 paralleling the rails R and R', the notches 9 being formed in the edges of the 20 strut on opposite sides of the portions 12.

A modified form of member may be provided, as shown in Fig. 9, with rails and struts of the same form as shown in Fig. 1, but in such form 25 each member includes a pair of struts S and S' secured to the rails R and R' in the same manner employed in the form shown in Fig. 1, but secured together at the alternate portions 12 by means of bands 13. In the last mentioned form of member, strut S is secured to rail R, strut S' is 30 secured to rail R' and the two struts are secured together, as described, thereby providing a member of double the width of the form shown in Fig. 1 but with only one additional member.

Members A, A, etc., of angular cross section 35 may be employed for supporting the lower ends of the rails R and R' whereby the studs may be attached to a sill, foundation or other supporting surface as by means of wire ties 14 laced through perforations 15 in said members and arranged at 40 uniform distances apart for varying the spacing of the studs thereon. Similar members A may be attached in the same or a different manner to the tops of the rails R and R' for providing headers for supporting rafters, joists or the like. 45 One or both sides of the members A may be provided with smaller perforations 16 alternating with the perforations 15 through which anchors, nails or other attaching devices may be threaded for attaching the members A to the 50 foundation, sill, rafters, joists or other structural members.

Thus, it will be noted that a stud or structural member constructed as shown and described herein is of truss-like character and may be 55 formed of light weight metal and yet, by reason of the particular cross sections shown and the strutted connections between the rails the members possess greater strength and resistance to lateral stresses than is possible with ordinary 60 sheet metal studs formed of single pieces of material. Moreover, there can be no waste material in the formation of the members and the openings between the strut sections 10 and 11 and the rails R and R' afford ample space for running pipes, 65 conduits and wires throughout the length of a wall structure at a minimum cost and with great facility.

When used in a wall as studs my improved structural members may be diagonally braced 70 by similar or different members suitably secured to the studs and to the sill pieces and headers A.

What I claim, is:

1. A fabricated steel structural member com-

prising: a pair of channeled rails having inwardly extending relatively wide sides, and a strut bent to form portions paralleling and so as to nest in the channels of said rails and of a width corresponding closely to the spacing of the sides 5 of the rail channels, said bent portions being adapted to abut the bottoms of said channels, and means for securing said strut to said rails at said points of abutment, said means including notches formed on the margins of the bent portions of 10 said strut and lugs bent from the channels of said rails at points near the bottoms of said rails and interlocking with said notches, said sides having their outer edges disposed in a common plane throughout the length thereof.

2. A fabricated steel structural member comprising: a pair of channeled rails having spaced sides inwardly turned, relatively right angular shoulders and a central longitudinal bead, and a strut having laterally formed flat portions adapted to engage the shoulders of said rails, said strut having oppositely bent portions at the junctions of which said strut engages said rails alternately, and means for securing said strut to said rails at said points of junction, said means including 25 notched portions on the margins of said strut and lugs on said rails interlocking with said notched portions, said sides having the portions between said lugs and their outer edges as well as said outer edges disposed in the same planes 30 as the remainder of said sides and edges.

3. A fabricated steel structural member comprising: a pair of rails of channeled cross section with inwardly turned sides, and a strut formed of a piece of material and bent in opposite directions for attachment to said rails at alternating points, said rails and said strut having correspondingly formed portions adapted to nest the abutting portions thereof at their points of attachment, and means for attaching said 40 members together at said points of engagement, said means including cooperating marginal interlocking portions on said rails and said strut, said correspondingly joined portions including 45 abutting flat portions extending longitudinally of said rails and strut and interfitted beads extending longitudinally in said rails and strut and between said abutting flat portions, said sides of said rails having their outer edges disposed in a 50 common plane throughout the length thereof.

4. A fabricated steel structural member comprising: a pair of channeled rails and a continuous strut therebetween bent to form alternating diagonal legs and intermediate attaching portions, the bottoms of the channels in said rails and the attaching portions of said strut at least being correspondingly formed in cross section, said strut attaching portions and said rails having marginal interlocking portions for rigidly holding said members together, said correspondingly formed portions comprising abutting flat portions and interfitted beads of arcuate cross section between said flat portions, said marginal locking portions comprising recesses cut in the 60 edges of said flat portions of the strut, and tongues struck from opposite sides of said rails and engaging in said recesses and overlying the said flat portions of said strut, said sides of said rails having their outer edges disposed in a 65 common plane throughout the length thereof.

HARRY W. HAHN.
